PASSBOOK

Edward A. Kelly, Indianapolis, Ind.

Application December 26, 1934, Serial No. 759,273

7 Claims. (Cl. 283—63)

This invention is a pass book of the coupon type, primarily designed for the recording of successive cash transactions of any character, although not limited to this specific use.

5 One of the objects of the invention is to provide a book of the character mentioned which will provide a simple and accurate record of successive cash payments, whether in the form of instalments on deferred payment purchases, 10 or the periodical payment on account of loans, or for any other use for which a pass book is commonly employed. A further object is to 15 guard against error by providing a simple form of pass book which includes a receipt form containing a plurality of continuously numbered spaces for the transactions to be entered, and a plurality of coupon pages or sheets associated with the receipt form, each coupon sheet consisting of a plurality of detachably connected coupons, 20 correlated to the spaces of the receipt form in such manner that each coupon will receive one entry as the data of the transaction is entered on the correlated space of the receipt form. By this construction and arrangement, the detached 25 coupons will serve as the collector's vouchers, the receipt form constituting the customers' record, the latter fully setting forth the number, date and the amount of each payment that has been made.

0 The invention will be hereinafter fully set forth and particularly pointed out in the claims.

In the accompanying drawing:

Figure 1 is a perspective view illustrating one of the groups of sheets arranged in accordance with the invention. Figure 2 is a plan view of one of the coupon sheets. Figure 3 is an edge view illustrating a book containing a plurality of groups of sheets. Figure 4 is a diagrammatic view illustrating the relation of the various sheets.

Referring to the drawing, 10 designates a coupon book which is made up of a plurality of sheets, arranged in a plurality of groups G, bound together in any desired manner, as for 5 instance, by staples 11, and if desired, a cover 12 and back 13 may be employed. Any number of the duplicate groups G may be employed.

Each group G consists of a receipt form R and a supplemental group consisting of coupon 0 sheets C¹, C², C³ and C⁴. Each group G may also include a carbon manifold sheet M, if desired. This sheet M, however, need not be bound in the book, but may be placed loosely between the leaves when used.

5 The receipt record comprises a sheet R having

a plurality of vertical columns R¹, R², R³, R⁴ and R⁵, said columns being horizontally ruled into a plurality of spaces R⁶, each of which is identified by suitable characters, such as indicated in column R¹. Column R² is arranged for the date of the payment, column R³ for the initials of the collector, column R⁴ for the entry of the amount paid, and the column R⁵ for the entry of the balance remaining after credit of the payment made. Obviously, the arrangement of columns may be varied to suit different conditions.

It will be noted that the coupon sheet C¹ of each group G is of approximately the same length as the receipt form R, but that the coupon sheets C², C³ and C⁴ are of progressively diminishing shorter lengths. It will be understood that the number of coupon sheets may be varied, the group consisting of a single receipt form R and four pages of coupon sheets having 20 been selected merely for illustrative purposes. In other words, the number of coupon sheets will vary with the number of the payments to be entered upon the receipt blank. It is to be understood, however, that the number of coupon 25 sheets should be equally divisible into the number of spaces R⁶ on the receipt form, and that the number of coupons must correspond to the total number of said spaces. In other words, the number of coupon sheets is dependent upon two 30 factors: (A) The difference in length between the coupon pages controlled by the "step down" indicated by the depth of each space R⁶; and (B) the difference between a satisfactory binding margin for the book, usually about one-half 35 inch, and the binding margin of each coupon sheet. Thus, with a coupon book in which the receipt is on a sheet five and one-half inches long, which is a typical length, the binding margin on the coupon sheet C¹ is one and one-half 40 inches. Subtracting one-half inch, which is a satisfactory binding margin for coupon sheets C⁴, provides a residual space M of one inch on coupon C¹. The depth of each space R⁶ on the receipt form R is one-quarter of an 45 inch, which is the key to the "step down", or difference in length between any two of the coupon sheets. By dividing the one inch residual space on coupon C¹ by one-quarter of an inch, the quotient will be four, indicating that each 50 group of coupon sheets should consist of four of such sheets. Inasmuch as the number of coupon sheets must be a multiple of the number of spaces R⁶, where there are sixteen spaces R⁶, as in the example shown in the drawing, it 55

will be found, upon dividing the number of spaces by the number of coupon sheets, that each coupon sheet should contain four coupons. In preparing a book of this kind, the foregoing calculation must be made. For instance, if the "step down" should be one-fifth of an inch and the extra binding margin on the sheet C¹ is one inch, provision may be made for twenty instalments by having five coupons to each coupon sheet. In other words, the construction is dependent upon the relation of the dimensions of the "step down" to the excess binding margin M on the first coupon sheet C¹, or the difference between the total binding margin on the first coupon sheet and the binding margin on the last coupon sheet.

In the illustration shown in the drawing, each coupon sheet is perforated to provide four separable coupons A, each coupon being provided with a space a', which is ruled as a duplicate of the vertical rulings of the receipt form spaces R⁶, so that each space a' will come beneath one of the horizontal spaces R⁶ of the receipt form. In other words, in the illustrated embodiment of the invention, the space a' has data for the date, the initials of the collector, the amount paid and the balance due. Each coupon is also provided with a space a² for an identifying character or payment number, and a space a³ for the account number. Between these spaces is a space a⁴ for any informative data that may be desired. The payment number characters in the spaces a² are duplicates of the serial numbers of the spaces R⁶ of sheet R.

It will be noted the coupons A are so positioned that the space a' of the No. 1 coupon of sheet C¹ will lie directly beneath the first space R⁶ of the receipt form sheet R, and that coupon No. 2 of the coupon sheet C² will lie directly beneath the second serially numbered space R⁶ on the receipt form R. Also, that the space a' of the No. 3 coupon, which is carried by sheet C³ will lie beneath the third space R⁶ of the receipt form R, and coupon No. 4, which is carried by the sheet C⁴ will lie beneath the space R⁶ designated by serial No. 4 of the receipt form R. The difference in length of the sheets C¹, C², C³ and C⁴ is such that the coupons respectively carried by the four sheets are staggered with respect to each other, in such manner that the coupons are arranged in sets running serially from top to bottom, so that the removal of any coupon of such a set, except the lowermost one will expose the next successively numbered coupon of the set immediately beneath and in register with the next serially numbered space R⁶ of the receipt form.

Assuming an account of \$20.00 to be paid, the entries would be as illustrated in Fig. 1. For instance, assuming a payment of \$1.50 on Sept. 26, 1933, the entry will be made on the first serially numbered space R⁶ of the receipt form R. That is, the entry consists of the date "9/26/33", the collector's initials "A. B. C.", the amount paid "\$1.50", and the balance due of "\$18.50". At the time that the entry is made in the first serially numbered space R⁶ in the receipt form R, the manifold sheet M is lying over coupon No. 1 with the space a' in register with said first space R⁶, so that exactly the same entry is duplicated on the coupon. After the entry has been made, the collector removes the coupon and returns the receipt form to the customer. By removing No. 1 coupon, which is carried by coupon sheet C¹, coupon No. 2, which

is the uppermost coupon of the same set carried by coupon sheet C², is then exposed, so that its space a' will lie beneath the space R⁶ on the receipt form R, which bears the serial No. 2.

Assuming a payment to be made on Oct. 26, 1933 of \$2.00, the entry will be "10/26/33, A. B. C., amount \$2.00, balance of \$16.50". Of course, the entry is similarly made on the space a' of coupon No. 2, which is removed by the collector, exposing coupon No. 3 in its position with space a' beneath space No. 3 on the receipt form R. Assuming another payment of Nov. 26, 1933 of \$5.00, the entries are made as before and the third coupon removed, exposing the No. 4 coupon beneath the numbered space 4 on the receipt form R. The removal of coupon No. 4 exposes coupon No. 5, carried by sheet C¹, which is the first coupon of the second set of coupons, and these operations are continued until the full amount is paid.

The advantages of the invention will be readily understood by those skilled in the art to which it belongs. For instance, the possibility of error is reduced to a minimum, because each transaction is completed at one writing, and eliminates the use of what is commonly termed a "blotter" record or diary record of cash receipts or payments. It is much more accurate than the old method of recording on a separate sheet, for the reason that the entry in the customers' pass book will naturally agree with the store record, because it is an exact duplicate. It will also be observed that the coupon book is capable of use for any purpose for which a pass book is commonly used, and is particularly useful in collecting instalments on deferred payment purchases, and the periodical payment of loans.

Having thus explained the nature of the invention and described an operative manner of constructing and using the same, although without attempting to set forth all of the forms in which it may be made, or all of the forms of its use, what is claimed is:

1. In a pass book, a receipt record comprising a group of sheets including a receipt form and a plurality of superposed coupon sheets beneath the receipt form, and means binding said sheets at one end and leaving them free at the other ends, said receipt form containing a plurality of successively positioned duplicate spaces for entry of payment data, said spaces being respectively identified by a series of different successive characters, each coupon sheet consisting of a plurality of detachably connected coupons, each provided with an identifying character corresponding to an identifying character of a space on said receipt form, each coupon having a portion normally in register with its identified space, all of the coupons being so disposed with respect to the receipt form and to each other that the coupons at the free edges of the respective successive sheets register with successively identified spaces of the receipt form, the coupon at the free edge of the topmost sheet being in register with the first space of said receipt form, all of the coupons being so arranged with respect to the spaces of the receipt form that as each coupon, except those of the last coupon of the set, is detached from its sheet the coupon indicated by the next successive identifying character on said receipt form will be at the free edge of the next coupon sheet, said coupon sheets and said receipt form being also so constructed and arranged that upon removal of the coupon

at the free end of any coupon sheet except the last sheet, the coupon on the free end of the next following sheet will be exposed beneath its identified space on the receipt form.

- 5 2. In a pass book, a receipt record comprising a group of sheets including a receipt form and a plurality of superposed coupon sheets beneath the receipt form, and means binding said sheets at one end and leaving them free at the other ends, said receipt form containing a plurality of successively positioned duplicate spaces for entry of payment data, said spaces being respectively identified by a series of different successive characters, each coupon sheet consisting of a plurality of detachably connected coupons, each provided with an identifying character corresponding to an identifying character of a space on said receipt form, each coupon having a portion normally in register with its identified space, the number of the coupons on each coupon sheet corresponding to the number of coupon sheets, and so arranged that the coupons are disposed in sets, each set including a coupon on each coupon sheet, with the respective coupons of the first set positioned at the free edges of the coupon sheets, the respective coupons of each set registering with the respective successively identified spaces of the receipt form, with the coupon at the free edge of the topmost coupon sheet in register with the first space of said receipt form, said coupons being so arranged with respect to the spaces of the receipt form that as each coupon except those of the last sheet is detached from its sheet, the coupon on any coupon sheet which coupon is indicated by the next successive identifying character will be at the free edge of the successive coupon sheet and will be exposed beneath its identified space on the receipt form.
- 10 3. In a pass book, a receipt record comprising a group of sheets including a receipt form and a plurality of superposed coupon sheets beneath the receipt form, and means binding said sheets at one end and leaving them free at the other ends, said receipt form containing a plurality of successively positioned duplicate spaces for entry of payment data, said spaces being respectively identified by a series of different successive characters, each coupon sheet consisting of a plurality of detachably connected coupons, each provided with an identifying character corresponding to an identifying character of a space on said receipt form, each coupon having a portion normally in register with its identified space, the number of the coupons on each coupon sheet corresponding to the number of coupon sheets, and so arranged that the coupons are disposed in sets each including a coupon on each coupon sheet, with the coupons of the first set positioned at the free edge of the respective coupon sheets, the respective coupons of each set registering with the respective successively identified spaces of the receipt form, the coupon at the free edge of the topmost coupon sheet being in register with the first space of said receipt form, said coupon sheets and said receipt form being so constructed and arranged with respect to the spaces of the receipt form that as each coupon except those of the last coupon sheet is detached from its sheet, the coupon on any coupon sheet which is indicated by the next successive identifying character will be at the free edge of its coupon sheet and will be exposed in a position beneath its identified space on the receipt form.
- 15 4. In a pass book, a receipt record comprising a group of sheets including a receipt form and a plurality of superposed coupon sheets beneath the receipt form, and means binding said sheets at one end and leaving them free at the other ends, said receipt form containing a plurality of successively positioned duplicate spaces for entry of payment data, said spaces being respectively identified by a series of different successive characters, each coupon sheet consisting of a plurality of detachably connected coupons, each provided with an identifying character corresponding to an identifying character of a space on said receipt form, each coupon having a portion normally in register with its identified space, the number of the coupons on each coupon sheet corresponding to the number of coupon sheets, and so arranged that the coupons are disposed in sets each including a coupon on each coupon sheet, with the coupons of the first set positioned at the free edge of the respective coupon sheets, the respective coupons of each set registering with the respective successively identified spaces of the receipt form, the coupon at the free edge of the topmost coupon sheet being in register with the first space of said receipt form, said coupon sheets and said receipt form being so constructed and arranged with respect to the spaces of the receipt form that as each coupon except those of the last coupon sheet is detached from its sheet, the coupon on any coupon sheet which is indicated by the next successive identifying character will be at the free edge of its coupon sheet and will be exposed in a position beneath its identified space on the receipt form.
- 20 5. In a pass book, a plurality of receipt records, each of which comprises a group of pages including a receipt form and a plurality of superposed coupon sheets beneath the receipt form, said groups being arranged in superposed relation, means for securing all of said pages at one end and leaving them free at their other ends, the receipt form of each group containing a plurality of successively positioned duplicate spaces for the entry of payment data, said spaces being correspondingly identified by a series of successive numbers, each coupon sheet consisting of a plurality of detachably connected coupons each provided with an identifying number corresponding to an identifying number of a space on the receipt form of its group, each coupon having a portion normally in register with its identified space, all of the coupons of each group being so disposed with respect to the receipt form of said group and to each other that the coupons at the free edge of the successive coupon sheets register with successively identified spaces of the receipt form of the group, the coupon at the free edge of the topmost coupon sheet being in register with the first space of its receipt form, each set of coupon sheets and its receipt form being so constructed and arranged with respect to the spaces of the receipt form that as each coupon except that of the last coupon sheet is detached from its sheet, the coupon indicated by the next successive identifying number on said receipt form will be at the free edge of its coupon sheet and will be exposed in a position beneath its corresponding numbered space on its receipt form.
- 25 6. A pass book comprising a group of sheets in-

cluding a receipt form and a plurality of super-
posed coupon sheets beneath the receipt form,
means binding said sheets together at one end
and leaving them free at their other ends, each
5 coupon sheet being provided with a plurality of
coupons, the receipt form containing a plurality
of successively positioned spaces, the number of
coupon sheets being a multiple of the number of
said spaces on the receipt form, the number of
10 coupons on each sheet also being a multiple of
the number of the spaces on the receipt form,
each coupon sheet being shorter in length than
the coupon sheet which immediately precedes it,
the first coupon sheet being of an excessive length
15 equal to a number of the spaces on the receipt
form which corresponds to the number of coupon
sheets, and each successive coupon sheet being
shorter than the coupon sheet which immediately
precedes it by an amount approximately equal
20 to the depth of one of the spaces on the receipt
form.

7. A pass book comprising a group of sheets
including a receipt form and a plurality of super-
posed coupon sheets beneath the receipt form,
25 means binding said sheets together at one end

and leaving them free at their other ends, each
coupon sheet being provided with a plurality of
coupons, the receipt form containing a plurality
of successively positioned spaces, the number of
coupon sheets being a multiple of the number of
said spaces on the receipt form, the number of
coupons on each sheet also being a multiple of
the number of the spaces on the receipt form,
each coupon sheet being shorter in length than
the coupon sheet which immediately precedes it, 10
the first coupon sheet being of an excessive length
equal to a number of the spaces on the receipt
form which corresponds to the number of coupon
sheets, each coupon sheet except the last one be- 15
ing of a length substantially in excess of that re-
quired for the number of coupons carried thereby,
the excess length being provided by a space
between the last numbered coupon on each sheet
and the binding means, and each successive
20 coupon sheet being shorter than the coupon sheet
which immediately precedes it by an amount ap-
proximately equal to the depth of one of the
spaces on the receipt form.

EDWARD A. KELLY. 25
